(57) **CLAIM**

The ornamental design for a hydroponic container, as shown and described.

DESCRIPTION

FIG. 1 is a perspective view of a hydroponic container showing my new design, wherein the hydroponic container is cylindrical;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of a hydroponic container showing my new design, wherein the hydroponic container is hexagonal prism shape; and,

FIG. 9 is a perspective view of a hydroponic container showing my new design, wherein the hydroponic container is rectangular.

In the drawings, the broken lines show portions of a hydroponic container that form no part of the claim.
